UNITED STATES PATENT OFFICE.

HARRY E. DONNELL, OF NEW YORK, N. Y., ASSIGNOR TO THE S. F. HAYWARD & COMPANY, OF SAME PLACE.

DESIGN FOR A HOSE-REEL SPOOL.

SPECIFICATION forming part of Design No. 29,104, dated July 26, 1898.

Application filed June 30, 1898. Serial No. 684,883. Term of patent 14 years.

To all whom it may concern:

Be it known that I, HARRY E. DONNELL, of the city of New York, borough of Manhattan, in the county and State of New York, have invented and produced a new and original Design for a Hose-Reel Spool, of which the following is a full, clear, and exact specification.

Reference is to be had to the accompanying drawing, forming a part of this specification, in which the figure is a perspective view of a hose-reel spool, showing my design.

The design consists of a hub A, from each end of which extend curved spokes B, arranged in pairs, the inner ends of the spokes

of a pair being separated and the outer ends thereof joining each other and terminating in a circular rim C and the inner end of one spoke in a pair joining the inner end of the adjacent spoke of the next pair.

20

The leading feature of the design consists of the hub and rim, with the intervening pairs of curved spokes.

I claim—

The design for a hose-reel spool, as herein shown and described.

HARRY E. DONNELL.
